PORTRABLE COMMODE

Harvey Eisenberg, 7 Demarest Road,
Livingston, N.J. 07039

Filed Aug. 25, 1965, Ser. No. 86,714

Term of patent 14 years

(Cl. D4—5)

FIG.1

Des. 208,352

PAGE 2

The back and the other side of the portable commode are the same as shown in FIGURES 2 and 3, respectively.

I claim:

The ornamental design for a portable commode, as shown and described.
